UNITED STATES PATENT OFFICE.

ZACHARY M. LINDLEY, OF CARTHAGE, MISSOURI.

SASH-BALANCE.

SPECIFICATION forming part of Letters Patent No. 616,947, dated January 3, 1899.

Application filed March 23, 1898. Serial No. 674,912. (No model.)

To all whom it may concern:

Be it known that I, ZACHARY M. LINDLEY, a citizen of the United States, residing at Carthage, in the county of Jasper and State of Missouri, have invented a new and useful Improvement in Devices for Controlling Balanced Window-Sashes, of which the following is a specification.

My improvement is directed to sash-balances in which the sash are connected by a balancing-cord controlled by a catch; and the precise improvement includes, in combination with the balancing-cord and its controlling-catch, a spring arranged to exert its tension downward upon the catch for aiding in raising the lower sash, as will be set out in the claims at the end of the description.

The accompanying drawings illustrate my said improvement, in which—

Figure 1 shows in elevation the window-sash with their connected controlling rack device. Fig. 2 is a vertical section of the same. Fig. 3 shows the sash-controlling rack device in enlarged views of the slotted side of the rack and in longitudinal and cross sections of the same.

To the lower sash and preferably mediate thereof is secured to the upper and lower bars a rack 1 of tubular construction, within which a catch is fitted to slide vertically in its function of controlling the raising and lowering of the upper sash. The tubular rack is preferably of sheet metal vertically slotted, the edges of the slot intersected by coincident transverse notches 2 at suitable distances apart and standing on the inner side of the sash. Within the slotted rack is fitted a slide adapted to engage the notches in the edges of the slot and provided for this purpose with a spring constantly tending to force the catch outward into engagement with the rack-notches. A simple construction for the sliding catch for this purpose is to form it of a plate with its upper edge 3 lipped outward, so that it will slide within the tube and effect its automatic engagement with the notches thereof as it is moved vertically within said tube. The sliding catch is a steel plate bent so that the slide part 4 will form the back to

the outer lipped part 5. By means of this sliding catch the sashes are connected to balance each other, the said connection being by

means of a cord 6, passed over a pulley 7, depending from the top of the frame and attached to the top bar 8 of the upper sash and 55 to the back plate 4 of the sliding catch. To the lipped part 5 of this catch is fixed a knob or handle 9, adapted to slide in the slot of the tubular rack and by which the catch is pressed inward to disengage it from the rack-notches 6c 22 when it is desired to slide the catch therein to open and to close the upper sash. When the upper sash is closed, the sliding catch serves to connect it with the lower sash, and the locking of the lower sash serves also to 65 lock the upper sash by means of the cord and its connected sliding catch.

Any suitable locking device may be provided for the lower sash, such device, as shown at 10, consisting of an eccentric-actuated 70 clamp fixed to the vertical bar of the sash for pressure against the frame.

The tubular rack being fastened mediate to the top and bottom bars serves to brace the sash when supporting the weight of the 75 upper sash.

To render it easier to raise the upper sash when open, I may provide a coil-spring 11 within the tubular rack connected to its upper end and constantly exerting its tension 80 downward upon the back part of the sliding catch, so that when the latter is pulled down to raise the upper sash the spring will contribute its lifting force upon the lifting descending movement of the slide. 85

Ordinarily the tubular rack will be in the vertical plane of the middle sash-bar; but it is obvious the rack may be applied to one of the sash-stiles.

It will be noted that the arrangement of the 90 catch within the rack also places the catch-connecting cord within the rack and within the coil-spring acting upon the catch.

While I have thus described the preferred embodiment of my invention, it will be evident to those skilled in the art that the details of construction may be varied without departing from the spirit of my improvement. 95

I claim—

1. The combination with the sashes, their 100 balancing-cord, a rack on the lower sash, and a catch engaging said rack and connected with said balancing-cord, of a coiled spring arranged to connect the rack and the catch

and exert its tension downward on the catch for the purpose stated.

2. In balanced window-sashes, and in combination with the sashes, a tubular rack secured to the lower sash, slotted vertically, the edges of the slot forming the rack, a catch vertically movable within said rack and having a spring-engaging function therewith, a coil-spring within the rack connecting its upper end and the said catch and having a

downward-acting force upon said catch, and a suspending-cord connecting said sliding catch and upper sash.

In testimony whereof I have hereunto signed my name this 23d day of March, A. D. 1898.

ZACHARY M. LINDLEY.

In presence of—

A. E. H. JOHNSON,

A. ROLAND JOHNSON.
